US0D1103722S

(12) **United States Design Patent** (10) Patent No.: **US D1,103,722 S**
(45) Date of Patent: ** Dec. 2, 2025

(54) **SCREEN PROTECTOR INSTALLATION DEVICE**

(71) Applicant: **Dongguan Pinjia Technology Co., Ltd.**, Guangdong (CN)

(72) Inventor: **Xiaofen Liu**, Guangdong (CN)

(73) Assignee: **Dongguan Pinjia Technology Co., Ltd.**, Dongguan (CN)

(**) Term: **15 Years**

(21) Appl. No.: **29/935,030**

(22) Filed: **Mar. 29, 2024**

(30) **Foreign Application Priority Data**

Mar. 26, 2024 (CN) 202430159801.7

(51) **LOC (15) Cl.** **08-05**

(57) **CLAIM**

The ornamental design for a screen protector installation device as shown and described.

DESCRIPTION

FIG. 1 is a top, front and right side perspective view of a screen protector installation device showing my new design; FIG. 2 is a front elevational view thereof; FIG. 3 is a rear elevational view thereof; FIG. 4 is a left side view thereof; FIG. 5 is a right side view thereof; FIG. 6 is a top plan view thereof; FIG. 7 is a bottom plan view thereof; FIG. 8 is a top, front and right side perspective view showing the screen protector installation device, with environmental matter shown by broken lines; and, FIG. 9 is another top front and right side perspective view showing the screen protector installation device in a closed condition, with environmental matter shown by broken lines.

The evenly dashed broken lines illustrate portions of the screen protector installation device and environmental subject matters that form no part of the claimed design.
